COMBINED CAN HOLDER AND PITCHER

Charles V. Greene, 73 Oakmont Drive, Oakmont, Del.

Filed Mar. 17, 1965, Ser. No. 84,315

Term of patent 14 years

(Cl. D44—21)

FIG. 4.

FIG. 1.

FIG. 3.

FIG. 2.

FIG. 5.

FIG. 1 is a front elevational view of a combined can holder and pitcher embodying my design;
FIG. 2 is a rear elevational view thereof;
FIG. 3 is a side elevational view thereof;
FIG. 4 is a top plan view thereof; and
FIG. 5 is a bottom plan view thereof.

I claim:

The ornamental design for a combined can holder and pitcher, substantially as shown.
